UNITED STATES PATENT OFFICE.

WALTER BIXBY, OF BOSTON, MASSACHUSETTS, ASSIGNOR TO SHAWMUT ENGINEERING COMPANY, OF BOSTON, MASSACHUSETTS, A CORPORATION OF MASSACHUSETTS.

TUBE FRAME FOR TUFT WEAVING.

Application filed November 6, 1923. Serial No. 673,055.

To all whom it may concern:

Be it known that I, WALTER BIXBY, a citizen of the United States, and resident of Boston, in the county of Suffolk and State 5 of Massachusetts, have invented certain new and useful Improvements in Tube Frames for Tuft Weaving, of which the following is a specification.

This invention relates to tube frames for 10 tuft weaving commonly used in the manufacture of Axminster carpets and other similar tuft fabrics, and is intended to provide an improved means for securing the individual tuft tubes firmly and accurately in operation 15 relationship to the carrier bar forming the backbone of the tube frame.

In my earlier pending application for U. S. Patent Serial No. 541,321, I described and illustrated a tube frame construction in 20 which the individual tuft tubes were supported in an aperture or slotted channel bar secured to the face of the carrier bar, the individual tubes being inserted through both of the parallel wings of the channel bar and 25 being detachably interlocked with one of said wings or flanges to facilitate removal of individual tubes without disturbing others. For most kinds of work this double flanged channel bar is entirely satisfactory. 30 In some cases, however, where the tuft tubes are required to be very short for any special reason, such construction is inapplicable, and the present invention is intended to provide a very firm and reliable means of 35 connecting the tube frame to the carrier bar, provision being made at the same time to prevent the chafing of the yarn against rough edges or contacts.

To this end the present improvement is 40 characterized by a tube-carrying and spacing-attaching member secured against the front face of the carrier bar and having its upper edge portion, that is, the edge nearest the yarn-spool, formed with a projecting 45 guard and tube-retaining ledge or rib, and at its lower portion with a single outwardly projecting tube-supporting and spacing slotted flange or ledge in which the individual tubes are inserted and held, the intake ends 50 of the tubes being secured by solder or equivalent means directly to the guard ledge which latter acts, by reason of its outward projection or overhang to protect the yarn from any roughness caused by the applied

solder. As the solder need be applied on 55 only to the upper end edges of the tubes abutting against the under side of the guard ledge, since the slotted flange affords a firm spacing support for the body of the tube, a firm anchorage of the tubes is secured 60 which can readily be disrupted in case it is desired to remove any individual tube from the tube-attaching member.

These and other features of the invention will be particularly explained in the following specification and will be defined in 65 the claim hereto annexed.

In the accompanying drawings I have illustrated a preferred form embodying the principles of the present improvement, in 70 which:

Figure 1 is a front elevation of the tube frame and its yarn-spool.

Figure 2 is a detail showing in perspective individual tubes inserted and attached 75 to the tube-attaching plate or member.

In Figure 1 of the drawings I have shown the tube frame embracing the usual yarn-spool 1, with its flanged heads 2, journaled in bearing brackets 3, which form the supporting connections between the carrier bar 6 and the yarn-spool. The carrier bar is supported by any usual or suitable suspension means, such as the well known suspension arm 4, and hook arm 5, for releasably suspending the tube frame as a whole 80 from an overhead carrier chain, not here shown.

Since the tuft tubes, on each cycle of operation, must pass between the warp threads 90 in the loom, it is obvious that they must be very accurately and uniformly spaced and must be held firmly in such spaced parallel relationship. Moreover, as the individual tubes are made of thin sheet metal they are 95 subject to injury, and when any of them become bent or distorted they should be readily replaceable with perfect tubes.

The tube-supporting and attaching member in this case comprises a longitudinal 100 strip 7, whose middle or body portion rests flat against the front face of the carrier bar 6, which, in this case, is shown of tubular construction and is secured thereto in any suitable manner, as by attaching screws 105 10. At its upper edge, that is, the edge nearest to the yarn-spool the attaching member is struck up to form a raised channel

grid or ledge 8, and its lower edge is bent at substantially right angles to the plane of the body to project outward and form a tube-spacing ledge 9 provided with closely arranged uniformly spaced slots or apertures 9₂, conforming in shape to the cross section of the body portion of the tuft tubes 11, so that the tuft tubes, which are tapered, may be inserted and seated therein from above with their extreme intake end edges abutting against the lower side of the guard rib 8.

When the individual tuft tubes have been inserted in this position they must necessarily stand in parallelism and at uniformly spaced intervals to permit their delivery ends to properly pass between the warp threads. A very light touch of solder applied to the extreme edge at the intake end serves to anchor each tube to the overhanging guard rib 8. Inasmuch as the slotted tube-attaching rib forms a firm support for the intermediate or body portion of the tubes, the application of but very little solder at the intake end edge is necessary to afford an adequately firm anchorage for the individual tubes and, therefore, this anchorage is easily disrupted when it is desired to remove any individual tube.

Ordinarily the application of solder at the intake edge of the tube would chafe the yarn, but as the solder in this case is applied below the outwardly projecting or overhanging guard rib, the infeeding yarn, passing through the tubes, will be suffi-

ciently raised from the points of application of the solder to prevent chafing.

In consequence of this construction the tubes can be very rapidly and accurately applied to the attaching member and individual tubes can be very easily removed therefrom by disrupting the solder connection and withdrawing the tube from its seat in the holding ledge.

In Figure 1 I have shown the tube-attaching plate member made in sections, but it will be understood that these members may be made of any desired length to suit particular needs, and in the case of very narrow tube frames a single section will suffice.

What I claim is:

In a tube frame for tuft weaving, the combination with a longitudinal carrier-bar, a longitudinal tube-carrying and attaching strip whose upper and lower edge portions are formed into integral outwardly projecting ledges, the lower ledge being transversely slotted to receive and support the individual tuft tubes, the upper ledge abutting against and overhanging the intake edges of inserted tuft tubes and forming a supplemental tube-retaining member to which the tubes are secured, and means for detachably securing the strip with its attached tuft-tubes to the front face of the carrier-bar, substantially as described.

In witness whereof, I have subscribed the above specification.

WALTER BIXBY.
